ABSTRACT

A method for securing structural support elements (slabs, piles, posts and the like) intended to erect power transmission lines. This method consists of forming an inclined opening in the element to be secured; in installing the said element in the soil so that the inclined opening faces the soil; and introducing a wedge via the inclined opening to be subsequently pressed into the soil.

Due to such a method of securing structural support elements, the reliability of securing the said elements in the soil with a non-deformed structure improves considerably and the bearing capacity of the elements increases sharply, the elements being able to take up loads in any direction.

METHOD OF SECURING STRUCTURAL SUPPORT ELEMENTS IN SOIL

FIELD OF THE INVENTION

The invention relates to structures for high-voltage power transmission lines and, more particularly, to methods of securing structural support elements intended for such lines. Among these elements are included concrete slabs, reinforced concrete, metal or wooden piles, support posts and the like.

BACKGROUND

As is known, the structural support elements are subjected to external loads such as change of wind direction, formation of ice on the wires of associated power transmission lines, as well as forces of soil bulging, and the like.

Widely known in the prior art are methods of securing structural support elements by means of driving piles. This method involves operations of fabricating piles, delivering them to the place of installation, driving the piles into the soil by means of a special mechanism.

A disadvantage of such methods consists of their limited application in thick soils. While driving the piles, and as they reach a certain depth, their further progress becomes impossible, since the force of soil resistance exceeds the strength of the pile proper thereby incurring damage to the latter.

A further disadvantage of such methods is the low bearing capacity of the piles as regards the dragging loads in weak soils due to the small perimeter of the pile and low friction between the surface of the pile and the weak soil.

To eliminate this disadvantage, structural support elements (support posts) have been installed on a foundation whose depth depends on the geological cut of the soil. Said foundation was in situ fabricated of concrete. For this purpose a falsework was constructed and the reinforcement housing and liquid concrete were installed therein. The foundation so formed could take up loads by its own weight.

An essential disadvantage of such a method consists of the high production cost of the foundation due to utilizing more materials, inconvenience of delivering them to the place of installation and so forth.

Still a further disadvantage of such methods involves the fact that much time has to be spent to provide the required strength of the concrete.

Also known in the prior art are methods of securing structural support elements (support posts) by means of braces fastened to the slabs. The mentioned method involves the following operations: digging pits to be used for laying slabs and mushroom-like foundations for posts at a depth of 2.5-3.5 m; filling up the pits with soil to be subsequently consolidated; and fastening the said braces to the upper portion of the vertical support post.

A disadvantage of such methods is involved in securing the support slabs and mushroom-like foundations in the soil with a damaged structure whose bearing capacity is much lower than that of the soil of natural formation. As a result of the change in the direction of wind loads, the braces drag the slabs out of the soil with a damaged structure and sag, and the post somewhat deflects from the vertical position to one or another side and can be overturned.

Another disadvantage of such methods involves the large amount of earthwork associated with digging the pits, filling them up with soil and consolidating the latter. All these operations deform the structure of the soil and reduce considerably the volume weight and the cohesion between the soil and the pit. Therefore, the efficiency of applying such methods is small.

Also known are methods of securing elements (support posts) on metal piles equipped with blades welded to the stem of the said pile. The mentioned pile is screwed into the soil and then the support element is secured to the pile above the level of its underground portion. Such a method of securing provides sufficient strength and normal operation of the pile in the soil with a non-deformed structure.

However, the production of such piles as well as the application of mechanisms for screwing them into the soil are costly. Also, in the process of screwing in the pile, the strength of the latter is impaired.

SUMMARY OF THE INVENTION

An object of the present invention is to eliminate the above-mentioned disadvantages.

Another object of the present invention is to reduce the amount of earthwork involved.

A further object of the invention is to reduce the consumption of additional construction materials and time required to install power transmission lines.

Still a further object of the present invention is to provide a simpler method of securing effectively the structural support elements in the soil with non-deformed structure.

This and other objects are accomplished in the method of securing structural support elements in the soil wherein, according to the invention, an inclined opening is formed in and through the element being installed so that the opening faces the soil and a wedge being introduced via the inclined opening presses it into the soil.

It is preferred to have additional inclined openings formed in and through the support element so that all the openings are in intersecting relation.

It is also preferred while securing structural support elements constructed in the form of a slab, to form the inclined openings at the corners of the said slab.

When securing structural support elements constructed in the form of a post, it is advantageous to form the inclined openings at one end, and lower this end of the post into the soil, and to rigidly secure a cup to the post above the level of the soil, the cup having guides slanting located so that their extensions in the direction of the soil intersect, with the guides serving to direct the wedges while they are introduced into the appropriate inclined openings of the post and while they are subsequently lowered into the soil. Upon completing the fastening of the support post by means of wedges, the said cup is removed.

Owing to the proposed method of securing the structural support elements (slabs, piles, posts and the like) in the soil, the amount of earthwork drops sharply. Besides, the reliability of securing these elements in the soil with a non-deformed structure improves considerably and the bearing capacity of the structural elements enables the latter to take up loads in any direction.

BRIEF DESCRIPTION OF THE DRAWINGS

A detailed description of the proposed method of se-

curing structural support elements is given below with reference to the accompanying drawings illustrating the subject of the invention, wherein:

FIG. 1 is a top view of an embodiment of the method for securing in the soil a structural support element constructed in the form of a slab with inclined openings that extend therethrough in intersecting relation;

FIG. 2 is a top view of another embodiment for securing a slab in the soil;

FIG. 3 is a general perspective view of securing a structural support element constructed in the form of a post with a cup being fastened to the upper portion of the post, the cup having guides which serve to introduce the wedges into the appropriate inclined openings.

DETAILED DESCRIPTION

The method of securing structural support elements constructed of the form of a slab consists in the following:

Formed through a slab 1 (FIGS. 1 and 2) are openings 2 inclined with respect to the upper and lower faces of the slab 1. There can be one or several openings depending on the bearing capacity of the soil and on the external forces acting on the support elements. The diameter of the openings and the inclination angle of the openings also depend on the same conditions. The said openings 2 can be formed at the corners of the slab 1.

The slab 1 is secured by means of wedges 3 inserted in the openings 2. Then by means of a special mechanism (not shown) the said wedges 3 are pressed into the soil without deforming its natural structure. The wedges can be fabricated from steel, reinforced concrete or other material of required strength.

The method of securing structural support elements having the form of a post 4 (FIG. 3) involves the following operations: forming the inclined openings 5 on and through one end of the post 4 with respect to its longitudinal axis and lowering the end of the post 4

with the inclined openings 5 into a pre-drilled well. Then, the cup 6 is rigidly fastened to the post 4 above the level of the soil. The said cup 6 has guides 7 which are inclined so that they would intersect if extended in the direction of the soil. The inclination angle of the guides 7 corresponds to the inclination angle of the openings 5. The inclination angle of the guides 7 is controlled by means of a goniometer (not shown) depending on the inclination angle of the openings 5. The wedges 8 are introduced via the guides 7 into the appropriate inclined openings 5 of the post 4. After that, the said wedges are pressed into the soil by means of a special mechanism.

Depending on the hardness of the soil, wells of smaller diameter than that of the wedge are pre-drilled, the wells corresponding to the inclined openings. Then in the above-described manner the wedges are pressed into the soil.

The loads are carried by the support post together with the wedges through which they are transmitted to the soil of a non-deformed structure, thereby insuring stability of the proposed designs at much higher values of loads compared to those designs which are employed at the present time.

What is claimed is:

1. A method of securing a structural support element in the soil, said method comprising forming the structural support element as a post, forming a plurality of inclined holes in one end of the post whose axes intersect, sinking said one end of said post in the soil such that said openings are below ground level, rigidly and detachably securing to said post above the level of the ground a cup having guides inclined to intersect said holes upon extension towards the soil, introducing wedges into said guides, driving said wedges into the soil so that the wedges enter said holes in the post and subsequently sink deeper into the soil, and removing said cup after the post has been secured by means of the wedges.
